UNITED STATES PATENT OFFICE.

JOHN C. EDWARDS, OF BROOKLINE, MASSACHUSETTS, ASSIGNOR TO A
KIMBALL COMPANY, OF NEW YORK, N. Y., A CORPORATION OF NEW
YORK.

PIN TICKET OR TAG.

No. 857,727.

Specification of Letters Patent.

Application filed January 26, 1907. Serial No. 354,270.

Patented June 25, 1907.

To all whom it may concern:

Be it known that I, JOHN C. EDWARDS, a citizen of the United States, and a resident of Brookline, county of Norfolk, State of Massachusetts, have invented an Improvement in Pin Tickets or Tags, of which the following description, in connection with the accompanying drawing, is a specification, like letters on the drawing representing like parts.

This invention has for its object the production of a novel pin ticket or tag for attachment to dress goods, garments, etc., in order to afford a convenient means for displaying price or other markings thereon, my present invention being designed for application to the fabric in such manner that the pin or prong-like fastener will pass through the same adjacent its edge. I have also provided the ticket or tag with means for protecting the pointed end portion of the fastener, so that it will not catch in adjacent fabrics or prick the fingers of those who have to handle the fabric.

The various novel features of my invention will be fully described in the subjoined specification and particularly pointed out in the following claims.

Figure 1 is a perspective view of a pin ticket or tag embodying one form of my invention; Fig. 2 is an edge view thereof; Fig. 3 shows the pin ticket applied to a fabric and secured thereto, but before the pointed end portion of the fastener is concealed; Fig. 4 is a similar view but showing the ticket in its final condition, as seen from the back of the fabric, with the fastener concealed; Fig. 5 is a sectional view on the line 5—5, Fig. 4, looking toward the left.

In accordance with my present invention I take a blank, made of paper, thin cardboard, or other suitable material and of the desired dimensions, and double it upon itself to form two plies 1, 2, which are superposed for a distance somewhat over half the length of the doubled blank, and these plies are permanently connected, as by cement, glue, or otherwise. The free end or extension of one of the plies, as 1, forms a fold 3, which is adapted to be bent over toward said ply along the line 4, 4, Fig. 1, and a rectangular opening 5 is made in the fold, extending from the bend toward the end of the fold. The free end of the other ply 2 forms a flap 6, and

it is shaped to present a tongue 7 of such width that it can be passed through the opening in the fold, as will appear hereinafter.

A fastener is attached to the connected plies adjacent the bend 4, 4, and opposite the opening 5 of the fold, and herein I have shown the fastener as a staple having pointed legs 8 and a connecting head 9. Conveniently the legs are passed through the ply 1 and the head 9 is held in place between the plies 1 and 2 by the permanent connection between them, the fastener being positioned before said plies are united.

The connected plies present a firm, smooth surface upon which price marks or other information is displayed, and in use this portion of the ticket rests against the face of the fabric to which the ticket is secured.

To apply the ticket the pointed ends 8 of the fastener are passed through the fabric from its face, adjacent its edge, see dotted lines Fig. 2, after which the fold 3 is turned or bent over the edge of the fabric and down upon its back face. In so doing the ends 8 of the fastener pass through the opening 5 in the fold, after which said ends are turned down laterally upon the outer face of the fold, as shown in Fig. 3. The ticket is now securely attached to the fabric, and it only remains to conceal and protect the turned down ends 8 of the fastener. To do this the flap 6 is bent over upon the fold 3 and the tongue 7 is passed through the opening 5, between the fabric and the fold, as shown in Figs. 4 and 5, the fold being held against the fabric by the turned down ends of the fastener, while the fold in turn retains the flap 6 in position to conceal and protect the fastener ends.

By making the opening 5 large enough to receive the fastener ends after they have been passed through the fabric the fold is easily turned or bent around the edge of the fabric, and will lie thereupon flat and smooth.

Any suitable fastener may be used, instead of the one herein shown, provided the general arrangement and construction of the ticket is preserved.

Having fully described my invention, what I claim as new and desire to secure by Letters Patent is:

1. As an article of manufacture, a pin ticket or tag doubled upon itself and cemented together for a part of its length, the free

2
5 end of one ply constituting a fold adapted to be turned over the edge of a fabric and having an opening therein, the free end of the other fold constituting a flap, and having a tongue to enter the opening in the fold, and an attaching fastener having a head positioned between the cemented plies adjacent the fold and adapted to pass through the fabric and then through the opening in and be 10 turned down upon the outer face of the fold, the flap covering the turned down portion of the fastener and being held in place by the tongue.

15 2. As an article of manufacture, a pin ticket or tag doubled upon itself and permanently connected for a part of its length, leaving a fold and a flap formed by the un cemented portions of the plies, said fold having an opening and the flap having a tongue to 20 enter the same, and a staple attached to the connected plies and adapted to pass through a fabric adjacent its edge and then through the fold when turned over the fabric edge, the staple being thereafter turned down upon 25 the fold and concealed by the flap when its tongue is inserted in the fold opening.

3. As an article of manufacture, a pin ticket or tag doubled upon itself and permanently connected for a part of its length, the 30 free end of one ply forming a fold and the

free end of the other ply forming a flap, a staple attached to the connected plies, to pass through a fabric adjacent its edge and then through the fold bent over the edge of the fabric, the staple legs when turned down 35 upon the outer face of the fold being concealed by the flap, and means to retain the flap in position to conceal the staple legs.

4. As an article of manufacture, a pin ticket or tag doubled upon itself and permanently connected for a part of its length, leaving a fold and a flap formed by the un cemented portions of the plies, a staple attached to the connected plies adjacent the fold and projecting from the face of said plies 40 toward which the fold is bent when in use, an opening in the fold extending toward its outer end from the bend, to receive the staple legs when passed through a fabric adjacent its edge, and a tongue on the flap to be 45 passed through the opening after the staple legs have been turned down upon the fold.

In testimony whereof, I have signed my name to this specification, in the presence of two subscribing witnesses.

JOHN C. EDWARDS.
